(72) Inventor: **Hoby R. Horn**, Moore, OK (US)

* cited by examiner

(73) Assignee: **Horn Equipment Company, Inc.**,
Moore, OK (US)

Primary Examiner — Cynthia Ramirez

(***) Term: **14 Years**

(74) *Attorney, Agent, or Firm* — Fellers, Snider,
Blankenship, Bailey & Tippens, P.C.

(21) Appl. No.: **29/440,713**

CLAIM

(22) Filed: **Dec. 26, 2012**

The ornamental design for a blowout preventer, as shown and described.

(51) LOC (10) Cl. **23-01**

DESCRIPTION

(52) U.S. Cl.

USPC **D23/233**

(58) **Field of Classification Search**

USPC D23/233–237, 244–249; 251/143, 148,
251/152, 309; 137/240, 412, 533, 801, 11

See application file for complete search history.

FIG. 1 is a perspective view of the blowout preventer showing my design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The broken lines in the figures are for the purpose of illustrating the environment in which the design is associated and form no part of the claimed design.
